WILLIAM OTTO MICHELSSEN, OF WOODHAVEN, NEW YORK

SPARK PLUG

Application filed April 3, 1929. Serial No. 352,185.

This invention relates to new and useful improvements in spark plugs which are especially adapted for use in connection with automobile internal combustion engines.

It is a known fact, that when starting an internal combustion engine while it is cold, by means of an electric motor that is supplied with electric current from a battery, which simultaneously is furnishing current for the ignition system of said engine, an arrangement that is generally embodied in the power plant of an automobile, that this battery is often overloaded by the heavy discharge that the starting motor imposes upon it. This heavy discharge is still further increased in cold weather when the oil in the engine is congealed and resists the efforts of the starting motor to a greater extent, effecting a considerable lowering of the voltage available for ignition of the engine. Frequently the gap formed between the spark plug electrodes, too wide for the purpose of starting the engine, causes failure to produce a spark until after the engine has been "turned over" a number of times and the resistance of the crank case oil has thereby been reduced. This is particularly true when the battery is not fully charged.

One of the principal objects of my invention is to provide a spark plug which will vary automatically the size of the spark gap in accordance with the temperature of the engine.

Another object of my invention is to provide the insulator of the spark plug with a recess which surrounds the central electrode in such a manner as to reduce to a minimum the danger of shortcircuiting between the central electrode, the insulator and the conductor shell to which the ground electrode is fixed.

Another object lies in the provision of a stop which cooperates with the movable electrode for limiting the minimum or subnormal size of the spark gap.

A further object lies in the provision of spaced stops for cooperation with the movable electrode to limit the minimum or subnormal and maximum or normal working sizes of the spark gap.

A still further object lies in the provision of a central electrode and a ground electrode which are each formed of a metal which is expansible under temperature changes and arranged in cooperative relation whereby the same will simultaneously move away from each other and thereby quickly change the spark gap size from a subnormal size to a normal or working size, and to provide spaced stops for each electrode to limit the movements thereof.

With these and other objects in view which will more fully appear, the nature of the invention will be more clearly understood by following the description, the appended claims, and the several views illustrated in the accompanying drawings.

In the drawings:

Figure 1 is a longitudinal sectional view of a spark plug embodying the preferred form of my invention.

Figure 2 is a complete view of the inner end thereof.

Figure 3 is a view similar to Figure 1 but showing another form of my invention.

Figure 4 is a complete view of the inner end thereof, and

Figure 5 is a complete end view of another form of my invention showing the structures of Figure 1 and 3 combined.

Like reference numerals designate corresponding parts throughout the several figures of the drawings.

Referring to the drawings and particularly to Figures 1 and 2, I have shown a spark plug which comprises a conductor shell A, an insulator B mounted therein and retained in position by a gland nut C, the inner end 5 of the insulator being disposed within the shell and the outer end 6 of the insulator projecting for a considerable distance beyond the gland nut. The outer end 6 of the insulator is provided with an axial opening 7 which communicates with a longitudinally and axially located recess 8, the latter having an uninterrupted surface and extending from the inner end 5 to a point beyond the gland nut C where it forms a resultant end wall or shoulder 9.

The inner end of the shell A is formed with

a reduced and exteriorly threaded extension 10 which constitutes an attaching end for the plug. This extension 10 is provided with an axial recess 11 and mounted in the recess 5 and seated against the wall thereof is a ground electrode comprising a coiled rod or wire 12 of copper or other suitable material which will expand and contract under temperature changes, the coil 12 including a plurality of axially aligned convolutions. One end 13 of the expansible coil 12 is fixed to the shell A by being mounted within an opening formed therein. The other end of the coil 12 is bent to form a longitudinally extending shank 14 which terminates in an inwardly and radially extending arm 15. Axially disposed within the recess 8 of the insulator B is a central electrode 16 comprising a rod 17 and a terminal arm 18. This rod 17 is substantially co-extensive with the insulator and the shell and the outer end of the rod is removably fitted within the axial opening 7 of the insulator. A flange 19 on the rod 17 is located within the recess 8 and cooperates with the end wall or shoulder 9 to prevent outward movement of the rod relative to the insulator. The outer end of the rod 17 projects beyond the insulator and is threaded as at 20. A washer 21 surrounds the threaded outer end of the rod 17 and bears against the end of the insulator. If desired an end cap 22 may be positioned on the rod 17 between the washer 21 and the insulator. Clamping nuts 23 have threaded engagement 25 with the threaded portion 20 of the rod for clamping the flange 19 tightly against the shoulder 9. A terminal nut 24 is also engaged with the threaded portion 20 of the rod for cooperation with the clamping nuts 20, 23 to secure a lead wire 25 to the central electrode. If desired, suitable packing may be interposed between the shoulder 9 and the flange 19. The opposite end of the rod 17 extends through the coiled ground electrode 45 12 and a transverse opening is formed adjacent the free end of the rod for receiving the arm 18. This arm 18 extends radially toward the arm 15 and is disposed in overlapping relation thereto to form a resultant spark gap X. The arm 18 is secured in the transverse opening of the rod 17 by a driving fit and consequently this arm may be renewed whenever desired.

From the foregoing, it will be observed 55 that when the ground electrode 12 is subjected to heat, the same will expand longitudinally and consequently the arm 15 will be moved away from the arm 18 of the central electrode and thereby the size of the spark gap will be 60 automatically increased. Normally the arm 15 is located quite close to the arm 18 so as to form therebetween a spark gap of sub-normal size which will permit the spark to readily pass from one arm to the other when 65 the engine is cold or when the battery is not

completely charged. In order to limit the minimum or subnormal size of the spark gap, I have provided a stop 26 attached to the extension 10 for cooperation with the shank 14 to limit movement of the arm 15 toward the arm 18. The normal or working size of the spark gap is determined by a stop 27 which is also fixed to the extension 10 for cooperation with the shank 14 to limit movement of the arm 15 away from the arm 18. 70 75

The diameter of the recess 8 in the insulator is considerably greater than the diameter of the central electrode 16 and consequently an air space is formed around that portion of the electrode which is located within the recess. Thus the rod 17 of the central electrode will become completely surrounded by high compressed gases at the time of each spark, and these compressed gases serve as an additional insulation between the rod and the gland nut. 80 85 This insulation is especially advantageous should the insulator be formed of porcelain or other porous material. By reason of the recess 8 extending beyond the gland nut, I have reduced to a minimum the possibility of shortcircuiting between the central electrode and the gland nut. 90

It is to be noted that the minimum distance between the rod 17 and the wall of the recess 8 is greater than the maximum spark gap distance. This is especially valuable in preventing shortcircuiting, as above noted, for the reason that porcelain insulators very soon absorb carbon. The microscopic cracks in the glaze become filled with carbon which penetrates the main body of the porcelain and soon causes it to become useless as an insulator. 95 100

Referring to Figures 3 and 4 which show another form of my invention, I have disclosed a conductor shell A, an insulator D arranged therein and held against movement by a gland nut C. The insulator D is formed with a recess 28 similar to the recess 8. The ground electrode 29 is fixed to the shell A and includes an inwardly and radially extending terminal arm 30. Located within the recess 28 is a central electrode 31 which includes a relatively non-expansible rod 32 and an appreciably expansible rod 33, the rods being 105 spot welded or otherwise rigidly connected as at 34, 34. The central electrode has its outer end mounted in an axial opening 35 formed in the insulator and is held against longitudinal movements relative to the insulator by an expanded socket 36 formed on the end of a projecting rod 37. The socket 36 is disposed within a recess 38 formed in the outer end of the insulator and a packing 39 of cement or other suitable material is disposed within the recess around the socket. A cap 40 is placed over the outer end of the insulator and is preferably cemented thereto. The rod 37 is threaded for engagement with a washer 41 and a clamping nut 42. A termi- 110 115 120 125 130

nal nut 43 is threaded on the projecting end 37 for cooperation with the nut 42 to clamp a lead wire therebetween.

The free end of the rod 32 of the central electrode extends past the arm 30 of the ground electrode and is spaced therefrom to form a spark gap X. When the rod 33 is expanded longitudinally under the influence of heat, the rod 32 will flex so as to cause the free end thereof to move away from the arm 30 of the ground electrode and thereby automatically increase the size of the spark gap X. In order to limit the minimum and maximum movements of the central electrode, and thereby determine the subnormal and normal widths of the spark gap, I have provided the insulator with spaced stops 44 and 45 respectively.

In the form illustrated in Figure 5, I have combined the structures shown in Figures 1 and 3 whereby both the central electrode 31 and the ground electrode 12 will be moved simultaneously in opposite directions to quickly increase the size of the gap X whenever heat is applied to the plug.

I claim:

1. In a spark plug, a conducting portion and an insulating portion, two electrodes respectively connected to said portions and forming a spark gap between said electrodes, one of said electrodes including a metal rod having a relatively high coefficient of expansion and movable in a direction under the influence of heat to increase the size of the gap, and a stop fixed to one of said members for cooperation with the expansible electrode to limit its movement toward the other electrode.

2. In a spark plug, a conducting portion and an insulating portion, two electrodes respectively connected to said portions and forming a spark gap between said electrodes, one of said electrodes including a metal rod having a relatively high coefficient of expansion and movable in a direction under the influence of heat to increase the size of the gap, and spaced stops fixed to one of said members for cooperation with the expansible electrode to limit its extreme movements toward and from the other electrode.

3. In a spark plug, the combination with a conductor shell, of an insulator mounted therein, a central electrode mounted in the insulator, a ground electrode connected to the shell and comprising a coiled rod expansible and contractible under the influence of temperature changes, said coil surrounding the central electrode and having one end disposed in cooperative relation to the central electrode to form a spark gap therebetween, and a stop fixed to the shell to limit the movement of the ground electrode in one direction relative to the central electrode.

4. In a spark plug, the combination with a conductor shell, of an insulator mounted

therein, a central electrode mounted in the insulator, a ground electrode connected to the shell and comprising a coiled rod expansible and contractible under the influence of temperature changes, said coil surrounding the central electrode and having one end fixed to the shell and having the other end free and disposed in cooperative relation to the central electrode to form a spark gap therebetween, and a stop fixed to the shell for cooperation with the free end of the ground electrode to limit the movement thereof toward the central electrode. 70 75

5. In a spark plug, the combination with a conductor shell, of an insulator mounted therein, and a ground electrode and a central electrode respectively connected to the shell and insulator and cooperating to form a spark gap therebetween, said electrodes being formed of metal responsive to heat to 80 thereby effect movements of the electrodes in opposite directions to widen the spark gap. 85

6. In a spark plug, the combination with a conductor shell, of an insulator mounted therein, a ground electrode and a central electrode respectively connected to the shell and insulator and cooperating to form a spark gap therebetween, said electrodes being formed of metal responsive to heat to 90 thereby effect movements of the electrodes in opposite directions to widen the spark gap, and stops respectively fixed to the shell and to the insulator and cooperating with the respective electrodes to limit their movements toward each other. 95 100

7. In a spark plug, the combination with a conductor shell, of an insulator mounted therein, a ground electrode and a central electrode respectively connected to the shell and insulator and cooperating to form a spark gap therebetween, said electrodes being formed of metal responsive to heat to thereby effect movements of the electrodes in opposite directions to widen the spark gap, and spaced stops respectively fixed to the shell and to the insulator and cooperating with the respective electrodes to limit their movements toward and from each other. 105 110

8. In a spark plug, the combination with a conductor shell, of an insulator mounted therein, a central electrode mounted in the insulator, and a ground electrode comprising a coiled rod having one end connected to said shell and having its other end disposed in cooperative relation to the central electrode to form a spark gap therebetween, both of said electrodes being formed of metal expansible and contractible under the influence of temperature changes to effect movements of the 115 120 125 two electrodes in opposite directions to vary the size of said spark gap.

9. In a spark plug, the combination with a conductor shell, of an insulator mounted therein, a central electrode mounted in the 130

insulator, and a ground electrode comprising a coiled rod disposed within the end of the shell and having one end connected to said shell and having its other end disposed in cooperative relation to the central electrode to form a spark gap therebetween, both of said electrodes being formed of metal expandible and contractible under the influence of temperature changes to effect movements of the two electrodes in opposite directions to vary the size of said spark gap.

10. In a spark plug, the combination with a conductor shell, of an insulator mounted in one end thereof, a central electrode connected at one end to the insulator and having its free end projecting beyond the end of the shell opposite the insulator, a ground electrode comprising a coiled rod having a plurality of axially aligned convolutions disposed within the end of the shell opposite the insulator in contact with the inner wall of said shell and extending around the central electrode, the inner end of the coil being connected to the shell and the outer free end thereof being disposed in cooperative relation to the free end of the central electrode to form a spark gap therebetween, said coiled rod being formed of metal responsive to heat to effect movement thereof and thereby vary the size of said spark gap.

30. In testimony whereof, I have hereunto subscribed my name.

WILLIAM OTTO MICHELSSEN.
